HIS ATTORNEY

UNITED STATES PATENT OFFICE.

EDWIN E. BARNEY, OF ILION, NEW YORK, ASSIGNOR TO REMINGTON TYPEWRITER COMPANY, OF ILION, NEW YORK, A CORPORATION OF NEW YORK.

TYPE-WRITING MACHINE.

1,133,697.

Specification of Letters Patent. Patented Mar. 30, 1915.

Application filed August 2, 1913. Serial No. 782,611.

To all whom it may concern:

Be it known that I, EDWIN E. BARNEY, citizen of the United States, and resident of Ilion, in the county of Herkimer and State of New York, have invented certain new and useful Improvements in Type-Writing Machines, of which the following is a specification.

My invention relates principally to type-writing machines and more particularly to the construction and mounting of the rotary platens of such machines. Roller platens are also used in machines other than typewriters and my invention is also applicable 15 or adaptable to such other machines.

My invention has for its principal object to provide a roller platen of inexpensive construction but thoroughly good and efficient for its purpose.

20 Another object of the invention is to provide improved means whereby the platen is detachably mounted in the machine.

To the above and other ends my invention consists in certain features of construction 25 and combinations and arrangements of parts, all of which will be fully set forth herein and particularly pointed out in the claims.

In the accompanying drawings, Figure 1 30 is a front elevation, partly in section, of the carriage of a typewriting machine having my invention embodied therein, the platen being shown in longitudinal section. Fig. 2 is a cross section of the platen. Fig. 3 is an 35 end view of said platen and the line space wheel with the platen shaft or axle shown in section. Fig. 4 is an end view of the carriage with the finger wheel removed. Fig. 5 is an end view of one of the pieces of wood 40 of which the core platen is made.

In the drawing parts of the typewriting machine not essential to an understanding of my invention are omitted.

The typewriter carriage shown in the 45 drawing, comprises end brackets 1 connected together by a bar or bars 2 constituting two grooved rails. Anti-friction balls 3 run between said rails 2 and a fixed stationary rail 4 suitably mounted on the stationary frame-work of the machine. The platen has an 50 axle 5 journaled in the end pieces 1 of the

carriage, and said platen also has a wooden core consisting of a plurality of pieces 6 fastened together around the axle 5. In the present instance, and preferably, there are 55 two of these pieces 6, each formed before being assembled with a half-round groove or cut-out 7, Fig. 5, extending longitudinally thereof so that when two of said pieces are put together face to face with the shaft 5 60 between them, said two grooves or cut-outs together form a round hole that fits nicely around the shaft. In order to fasten the core rigidly to the shaft a hole is bored transversely through the shaft and a nail 8 65 is driven through the hole into one of the sections 6 of the core, and the other half of the core is then put in place and the two parts of the core are glued together. In the present instance the nail 8 is shown driven 70 only into one of the halves of the core but when driven into that one it can be allowed to project beyond the shaft and the other half or section of the core can be forced down over it. It will be seen that the shaft 75 is thus practically nailed to the core and that the nails cannot get misplaced because they are placed in between two parts that are glued together. It will be understood that the part 8, which, for convenience, I 80 have called a nail, can be of any suitable character, such as a screw, brad or staple, or merely a piece of wire. Preferably, the two core sections are made originally in the form shown in Fig. 5, each consisting in effect of 85 a piece of molding formed with the half-round groove 7 and with the corners rounded off as shown. After the two sections have been fastened together over the axle and after the glue has dried, the core is then 90 turned down to size on the shaft, after which said core is inserted in a cover 10 consisting of rubber or other suitable material. This cover is preferably of the sort ordinarily used on typewriter platens. 95

It will be observed that the nailing is done from the inside of the core, so to speak, and that the nails terminate interiorly of the wooden core. By reason of this fact the breaking away of the wood at its outer surface is avoided, and moreover the nails do not interfere with the operation just de- 100

scribed of turning the core down to size after it has been fastened to the shaft.

It will be perceived from the description above given that the wooden core of the 5 platen is firmly fastened to the shaft. Any suitable number of nails 8 can be used, two being shown in the present instance. I secure a line space wheel 11 to one end of the platen. On account of the manner in which 10 the core is fastened to the shaft, this line space wheel does not require to have any hub or to be itself fastened directly to the shaft. Preferably the line space wheel consists of a plain ratchet wheel made out of sheet metal 15 of appropriate thickness and having the ratchet teeth formed around its periphery and having holes made in it for wood screws 12 which screws are screwed into the end of the wooden core. I have shown an escutcheon 13 consisting simply of a disk of sheet metal perforated for the platen axle and also for nails 14, said escutcheon being nailed to the end of the core opposite that on which the line space wheel is mounted.

20 25. In order to mount the platen detachably in the carriage, the axle 5 of said platen lies in an open slot 15 in each of the end pieces 1 of the carriage and on each end of said axle there is mounted a sleeve 16, the inner 30 end of which is journaled in a counter-bore or cut-out 17 in the outer face of the adjacent end piece 1 and concentric with the bottom of the slot 15. These sleeves preferably consist of the hubs of the finger wheels or 35 twirlers 18. The counter-bore is made of such a diameter as that the inner end of the hub takes a bearing therein and as the diameter of the counter-bore and of the hub is greater than the width of the slot 15, this 40 bearing prevents the shaft from rising in the slot. The platen can, however, be readily detached by moving one of the finger wheels a short distance away from its normal position on the shaft. To this end, one of the 45 finger wheels is fastened on the shaft by means of a set screw 20 which can be readily loosened and the finger wheel be allowed to be moved lengthwise of the shaft out of the counter-bore 17. This also allows the shaft 50 itself to be moved in the opposite direction so as to bring the other hub 16 out of its counter-bore, after which the platen and shaft can be lifted out of the machine. I prefer to fasten one of the hubs 16 on with 55 a set screw and the other with a pin 21 passing through the hub and shaft. This or some equivalent construction is advisable in order to give a definite location to the platen. If both finger wheels were fastened 60 on with set screws and both said screws should be loosened at the same time, the next time the platen was put into the machine it might be put in a little farther to the right or to the left than before, in which

event the line space wheel might not co-operate properly with the line space pawl, detent and so forth. The pin 21 prevents this likelihood of change of position. It will, of course, be understood that any other ordinary device can be substituted for said 70 pin, provided said device has the property mentioned, namely, that of locating the hub lengthwise of the shaft. It will be noted that the hubs 16 and counter-bores 17, perform the double function of detachably securing the platen in place, and also of preventing endwise motion of said platen in its 75 bearings.

Various changes can be made in the details of construction and arrangement, without departing from my invention.

What I claim as new and desire to secure by Letters Patent, is:—

1. A platen comprising in combination an axle and a wooden core nailed directly to 85 said axle, the nails passing through the axle and extending outwardly therefrom and terminating in the interior of said wooden core.

2. A platen comprising in combination an 90 axle, a core consisting of a plurality of pieces fastened together around said axle and at least one of said pieces nailed to said axle, and a cover on said core.

3. A platen comprising in combination an 95 axle, a core consisting of a plurality of pieces fastened together around said axle and at least one of said pieces nailed to said axle, a cover on said core, and a line space wheel secured to said core.

4. A platen comprising in combination an 100 axle, a core section to which said axle is nailed, and another core section glued to the first core section over the nails.

5. A platen comprising in combination an 105 axle, a core section to which said axle is nailed, another core section glued to the first core section over the nails, and metal fixtures fastened to the ends of said core.

6. A platen comprising in combination an 110 axle, a core section to which said axle is nailed, another core section glued to the first core section over the nails, and a line space wheel secured solely to said core.

7. A platen comprising a sectional wooden 115 core and a central metallic shaft, said shaft having projecting nails which enter said wooden core and terminate interiorly thereof.

8. The combination of a roller platen having an axle, a carriage having parts having open ended slots in which said axle is journaled and said parts also being counter-bored, finger wheels having hubs sleeved on to said axle and secured thereto and said 125 hubs entering said counterbores to prevent the axle from rising in said slots, at least one of said hubs being movable on said

axle to permit the detachment of the platen, and means definitely to locate the other hub lengthwise of the axle so as to insure that the platen after being removed and replaced shall always occupy the same position as before with relation to said parts.

Signed at Ilion, in the county of Herki-

mer, and State of New York, this 31st day of July A. D. 1913.

EDWIN E. BARNEY.
